WALL CONSTRUCTION

Frank R. Schaaf, Meriden, Conn.

Application August 29, 1938, Serial No. 227,413

3 Claims.

(Cl. 72—48)

My invention relates to improvements in wall constructions and also to an improved method and an apparatus for forming or constructing the same.

5 One of the principal objects of my invention is to provide wall units of a precast construction adapted to be arranged in a manner whereby concrete or the like may be readily associated therewith to form a wall or the like without subsequent removal of said units.

10 Another object of my invention is to provide a wall construction which is extremely strong and durable and one which may be quickly and economically fabricated and within a minimum 15 amount of time.

Other objects relate more particularly to the provision of an improved method of an apparatus for building such a wall.

Other objects and advantages will be apparent 20 from the following description, appended claims and annexed drawing.

Referring to the drawing wherein like reference characters designate like parts throughout the several views:

25 Figure 1 is a side elevation of a number of my wall units associated together and illustrating one step in the construction of a wall or the like.

Figure 2 is a sectional view taken on the line 30 2—2 of Figure 1.

Figure 3 is a view similar to Figure 2 illustrating another step in the construction of my novel wall.

Figure 4 is a longitudinal sectional view illustrating the portion of a ceiling and floor constructed in accordance with my invention.

Figure 5 is a fragmentary perspective view of one of my wall units.

Inasmuch as each of my novel forms of wall 40 units are of a substantial like construction, a description of one will suffice, it being understood that reference characters indicative of parts of one unit are likewise indicative of the same parts of the other units.

45 My building unit 5 comprises a latticed structure made up of a plurality of spaced vertically and horizontally extending ribs 6 and 7 respectively, said ribs coacting together to form therebetween interstices 8. The ribs 6 coact together to form vertically extending channels 6a and likewise the ribs 7 coact together to form horizontally extending channels 7a. Each of the units 5 are constructed of a mixture of cement 50 and sand and are arranged relative to each

other to form a skeletonized frame work for a wall or the like.

As illustrated in Figures 1 and 2 of the drawing, the units are set up to form a pair of spaced inner and outer wall frames 9 and 10 respectively. The outer face of the frame 9 has secured thereto studs 11 by means of wires 12. The inner face of the frame 9 has secured thereto a body of insulating material 12 and extending through said material 12 and securing the inner 10 and outer frames 9 and 10 together are wires 13. The insulating material 12 coacts with the ribs 6 to form vertically extending dead air spaces within the channels 6a as clearly illustrated in Figures 2 and 3 of the drawing.

When the frames are thus set up, concrete or the like is poured between the frame 10 and insulating material 12 and exudes through the interstices of the frame 10 and is floated or troweled over the outer face thereof to form a smooth and neat appearance. Suitable plastic material 15 is applied to the outer face of the frame 9 and floated or troweled thereover. Said plastic material enters the interstices thereof and effects anchorage with said frame 9. However, it is to be distinctly understood that the insulating material 12 may not necessarily be used. Thus, when the concrete 14 is poured between the frames said concrete will exude through the interstices of both of the frames and may be floated over the outer surfaces thereof. It is to be further understood that before the outer surfaces of the frame 9 are dressed, the studs 11 are removed therefrom. Furthermore, other plastic material may be applied to the outer faces of the frames 9 and 10 and secured thereto by cohesion with the concrete exuded between the interstices.

With particular reference to Figure 4 a floor and ceiling construction may be quickly arranged 40 by connecting a pair of horizontally disposed frames made up of my novel units 5 and connected together by pairs of transversely extending units. For a construction of this character horizontally extending spaced beams are initially provided supported by vertical members. When thus arranged, concrete is poured into and between the vertical extending units and over the uppermost horizontally extending frames and 45 allowed to set.

When the concrete has thus become set, the beams are removed and a plaster or the like 50 may be applied to the lower face of the lowermost horizontally extending frame in the same 55

manner as heretofore set forth in the instance of the inner frame 9 of a vertically extending wall. From the foregoing it will be apparent that I have provided a simple apparatus and method whereby walls and the like may be easily constructed without the necessity of removing forms therefrom and within a minimum amount of time, thereby effecting an economy in material and labor.

10 It is to be distinctly understood that various changes and modifications may be resorted to in the arrangement of parts and that other like materials may be substituted without departing from the spirit of the invention or scope of 15 the appended claims.

What I claim is:

1. A new article of manufacture, comprising, a precast integrally fashioned latticed building unit of plastic material having interstices for

receiving other plastic material therein for anchorage to said unit to form an integrant thereof.

2. A new article of manufacture, comprising, a precast integrally fashioned building unit having a plurality of connected and angularly related elements of plastic material defining a lattice having interstices for receiving other plastic material therein for anchorage to said unit to form an integrant thereof.

3. A new article of manufacture, comprising, a precast integrally fashioned building unit of a latticed construction having sets of spaced ribs, the ribs of one set being disposed laterally of the other set and extending angularly relative thereto a sufficient degree to provide interstices between said ribs for receiving plastic material therein for anchorage to said unit to form an integrant thereof.

FRANK R. SCHAAF.
